CONCRETE ROAD JOINT

Clifford Older, Wilmette, Ill.

Application November 17, 1937, Serial No. 175,128

5 Claims. (Cl. 94—18)

The present invention relates to concrete road joints, and is particularly concerned with concrete road joints adapted to permit expansion and contraction of the concrete and to maintain the concrete slabs in alignment without damage to the roadway, due to such contraction and expansion.

This application is a continuation in part of my prior application, Serial No. 80,281, filed May 10, 1936, for Concrete road joints, and relates particularly to one of the modifications disclosed in that application.

One of the objects of the present invention is the provision of an expansion joint of the air cushion type, the length of which may be adjusted as desired, in the field, just before the installation of the joint.

The air cushion type joints of the prior art are at present fabricated in the shop to a fixed length. In the event of a mistake in the determination of the length of the joint, which might and does happen more frequently on joints of various lengths which are used on curves, the pre-fabricated joints would prove too long to go 25 between the side forms.

In such case this causes a controversy between the contractor, the engineer, and the expansion joint manufacturer, with the result that the manufacturer must either provide a new joint or 30 pay the additional cost of widening the pavement to fit the joint which he has provided. Such errors sometimes happen in the determination of the length of joints for a long stretch of road, in which case it may cause the joint manufacturer a great deal of cost to furnish an entire new batch of joints or to pay the additional cost of widening miles of pavement, including the cost of adapting the contractor's templates, etc. to the odd width.

40 It will, therefore, be evident that it is a matter of considerable importance to provide for the adjustment of the length of the air cushion joints in the field.

Another object of the invention is the provision 45 of an improved concrete road joint of the air cushion type which permits the building up of any length of joint of simple standard length parts, except as to the length of the dowel plate and seal caps, which can be quickly cut to the 50 proper length either in the shop or field. This arrangement effects a surprising economy in the manufacture of concrete road joints.

Another object of the invention is the provision 55 of an improved concrete road joint of the air cushion type, which employs parts of fixed

standard dimensions which are so assembled that the length of the complete joint may be varied within certain limits.

The need for this variation arises from the fact that while the tangents or separate portions of the pavement are usually of one width, for example, twenty feet, the width on curves is often increased by varying amounts, depending upon the sharpness of the curve. The same is true at intersections, Y junctions, etc. 10

It is a frequent occurrence, therefore, that all sorts of odd length of joints are required.

In the present state of the art, metal air cushion joints are constructed as a complete rigid metal envelope unit in the shop, and the odd 15 lengths are marked for particular locations in the pavement. Such odd lengths can be used nowhere else, as the construction is such that it is entirely impractical to alter the length of the joint in the field. This actually causes much expense in taking proper lengths off the plans, building the special lengths, distributing them to proper locations in the field, and marking each of them for its proper place. It is well known that this necessity for special lengths is 20 a source of much trouble and expense.

The present invention relates to such a construction, as it permits an easy field adjustment of a standard joint to any special length within predetermined limits. 30

Another object of the invention is the provision of such an adjustable length air cushion joint for concrete roadways which may be assembled in the field as a unit and secured together to be self-supporting when installed upon the terrain 35 for the laying of the concrete.

Other objects and advantages of the invention will be apparent from the following description and the accompanying drawings, in which similar characters of reference indicate similar parts 40 throughout the several views.

Referring to the three sheets of drawings:

Fig. 1 is a fragmentary side elevational view of a concrete road joint constructed according to the present invention, shown in proper position for installation of the concrete; 45

Fig. 2 is a larger vertical sectional view taken on the plane of the line 2—2 of Fig. 1, with the concrete in place, showing the complete construction of the roadway; 50

Fig. 3 is a vertical fragmentary sectional view, taken on the plane of the line 3—3 of Fig. 2, showing the details of construction at one of the points where sections of the joint shield adjoin 55

each other, with the top and bottom short seal sections omitted;

Fig. 4 is a view similar to Fig. 3, showing the complete structure of the joint, as the top and bottom short seal sections have been included;

Fig. 5 is a vertical fragmentary sectional view of the upper part of one of the joints, similar to the view of Fig. 2, except that it is taken at the point 5-5 of Fig. 4, between the ends of two of the sections of the shield;

Fig. 6 is a vertical elevational view of one of the end cover plates and clamping members;

Fig. 7 is a top plan view of the end cover plate and clamping member of Fig. 6;

Fig. 8 is a view in perspective of an air cushion joint of the type described, with certain parts broken away or omitted, so as to show many of the details of construction of the joint in one drawing;

Fig. 9 is a view in perspective of an end closure plate and clamping member of the type shown in Figs. 6 and 7.

Figs. 10, 11 and 12 show the preferred shapes of the joint at the edge of the pavement.

Referring to Fig. 8, 10 indicates in its entirety the concrete roadway joint, which is adapted to be installed as a unit, but may be altered as to length on the job. The joint preferably includes a dowel plate 11, which may consist of a strip of steel of predetermined thickness adapted to withstand any shearing forces which might be applied to it, and to transmit load from one concrete slab 12 to the other 13 (Fig. 2).

The upper and lower surfaces 14, 15 of the dowel plate are parallel to each other and are adapted to slidably engage the parts of a shield, further to be described. The width of the dowel plate is such that it projects into each of the concrete sections 12 and 13, and extends across the air space of the joint, but leaves a space 16, 17 between the dowel plate 11 and the shields (Fig. 2) 18, 19 for initial expansion of the concrete.

The dowel plate material may be provided in standard lengths, and where the joint is installed as a unit is preferably all in one length, extending from one edge of the pavement to the other side, but does not necessarily extend the extreme edge of the pavement, as it may be shorter and still support the other parts of the joint to provide a movable unit. Additional dowel plate material is preferably provided in the field with a shear or hack-saw, so that it may be cut to proper length to adjust the joint to the odd lengths required for curves, intersections, Y junctions, etc.

The shields 18 and 19 may be similar in shape and construction except that they are reversed in position on the dowel plate, as shown in Fig. 2, and therefore a minimum number of standard shapes of shield are required for the central portions of the joint. Figs. 10, 11 and 12 show the preferred pavement sections at the edges of the pavement, and shields for this part of the pavement will be made at the shop to fit the desired cross section of the pavement adjacent the edge of the roadway. This effects a great economy in the manufacture of the joint.

The shield is made of relatively thin sheet metal, such as steel, which is resilient, yet relatively stiff. The shield 18, for example, has a substantially U-shaped central portion surrounding the air space 16 at the edge of the dowel plate 11, and comprises the upper flange 20, lower flange 21, and a U-shaped bend or easy curve 22.

The upper flange 20 supports an upwardly extending flange 23, which extends up into the flexible expandable member 24. The lower flange 21 of the shield 18 supports a downwardly extending flange 25, which extends downward into the lower flexible member 26.

Flanges 23 and 25 are preferably at right angles to the flanges 20 and 21, and the flanges 23 and 25 are preferably in the same plane. The dowel plate 11 is preferably approximately midway between the top and the bottom of the concrete, to utilize the strength of the concrete thickness to the best advantage for load transmission. Their width is such that with the flexible members 26 and 24, the flanges 23, 25, and 15 U-shaped bend 22 substantially span the depth of the concrete; but I prefer to leave the upper seal 24 slightly below the surface and round off the edge of each concrete section to the inner surface of the flexible member 24 at the points 20 27, 28 with an edging tool.

The construction of the other shield is substantially the same, and therefore need not be described in detail.

Since it is desirable to locate the top of the joint below the top surface of the concrete, for the protection of the joint from traffic, the flange 23 may be narrower than flange 25 by an amount sufficient to secure these results.

Various types of flexible members 24, 26 or 30 sealing members may be employed, but I prefer to employ a sealing member of the shape shown, which has a central expandable portion 29 having a substantially flat bottom 30 and a pair of upwardly extending walls 31, 32.

At the top of the walls 31, 32 there is an easy bend or substantially cylindrical bead 33, 34, to the edge of which is connected a downwardly extending flange 35, 36 at each side. The downwardly extending flanges 35, 36 are preferably 40 longer than the flanges 31, 32, for a purpose further to be described; and they support the anchoring flanges 37, 38, which extend into the concrete sections 12, 13, and are anchored therein by any suitable anchoring formation, such as 45 an upwardly turned edge 39.

The vertical flanges 31, 35 and 32, 36 are adapted to receive between them the upwardly extending flanges 23 of the shields 18 and 19. The seal or flexible member 24 is preferably 50 made of non-corrodible bendable material, such as copper, and the width of the bottom flange 30 of the seal is determined by the initial air space desired in the joint, as will be further discussed hereinafter.

Such a sealing member 24, 26 is preferably mounted at the top and at the bottom of the joint, but in other embodiments of the invention the sealing member may be replaced by strips or blocks of rubber or other elastic material for closing the top and the bottom of the joint. In any event, the uppermost sealing member 24 has its trough preferably filled with an initially plastic filler 40 to prevent ingress of undesirable elements, such as sand and rock, which might be 65 compressed between parts of the seal or concrete sections to the detriment of the joint.

In some embodiments of the invention the beads 33, 34 may be provided with a wire filler 41 or a filler of compressible material, such as a 70 cord of jute, hemp, cotton, or the like, the purpose of the filler being to provide support for the uppermost edges of the shield flanges 23, so that these shield flanges will not cut into the beads 33, 34, but will be spaced therefrom.

In other embodiments of the invention, as shown in Fig. 2, the clamping members 42, 43 may extend upward far enough to engage the under sides of the anchoring flanges 37, 38 to hold the sealing member 24 with its beads 33, 34 up above the air space from the edges of the shield flanges 23.

The upper and lower flanges 20 and 21 of the shields 18, 19 slidably engage the dowel plate 11; but, due to the thinness of the material of which the shields 19 and 20 are made, the clamps 42 and 43 are provided for holding the flanges 20 and 21 in tight sliding engagement with the dowel plate 11.

16 Each clamping member preferably comprises the central U-shaped portion 44, which may be provided with the upper and lower parallel flanges 45, 46. These parallel flanges are joined by the U-shaped bend 47, which embraces the 20 similarly shaped portion of the shield 18 in such manner that the walls 20 and 21 of the shield are clamped in tight sliding engagement with the dowel plate 11.

The clamping members 42, 43 each have the 25 upwardly extending members 48, which are adapted to support the vertical flanges 23 of the shields by engaging on the outside of these flanges.

I prefer, however, to use a minimum number 30 of gaps in the top and seal members, as the fewer splices used in the seal, the better and more tight the seal construction will be.

In some embodiments of the invention the operator can be provided with suitable lengths of 35 seal which can be cut off with the tin shears or hack-saw to the length of the joint, and the seal can be made all in one piece, spanning all of the gaps in the shields.

In other embodiments of the invention, the 40 joint may have but one splice in the seals and at the middle of the road where it is not as objectionable to provide an opening as it is towards the sides. The middle of the road is at the crown or the high part of the pavement, 45 where there is a minimum of water and dirt.

Therefore, I wish it to be understood that in the preferred embodiment the seal gaps may be provided in two equal lengths with an adjustable splice 63 at the center of the roadway 50 covering the gap 57A.

The clamping members 42 and 43 are identical in shape, and therefore only one of them need be described. Below the U-shaped portion 44 of the clamping member 43 there is a downwardly 55 extending leg 49 located in the same plane as the upwardly extending member 48 and engaging the outside of the downwardly extending flange 25 of the shield 18. The leg 49 is bent outward at 50, and downward again at 51, so as 60 to extend around the parts of the lower flexible member or seal 26.

The downwardly extending portion 52 and other lower parts of the clamp may be long enough to hold the joint up high enough so that 65 the lower edges of the flanges 25 of the shield are held up out of the beads of the sealing member 26. In other embodiments of the invention the bottom seal beads may be provided with wires or other fillers like the top seal. In other 70 embodiments a temporary seal may be used at the bottom, as shown at 26A, without anchor flanges. Each clamping member is preferably provided with an outwardly extending foot flange 53, which preferably has an aperture 54 for receiving a stake 55, driven into the terrain 75

through the aperture 54, and preferably so located that its upper end bears against the U-shaped bend 47 of the clamping member 44. By means of two such stakes as shown in Fig. 2, the fixity and assembly of the joint during the 5 pouring of the concrete is assured, although the clamping members are sufficient to hold the joint together so that it may be installed as a unit.

Referring to Figs. 1 and 8, the shields 18 and 19 are preferably constructed in the form of a plurality of lengths or sections 18, 18a, 18b, etc., and the lengths of the sections may be such with respect to the width of the pavement that there is a gap 56, 57 between the ends of the shield 15 sections.

Such a gap may, for example, amount to two or three inches, and the clamping members 42, 43, which are indicated by 43, 43a and 43b in Fig. 1, are preferably of heavier material and 20 wider stock so as to overlap the shields on each side of the gap 56. The clamping members may, for example, be approximately six inches wide, except at the end, where they may be made narrow, as shown at the right side of Fig. 1. 25

The shield members may also have their flanges 23 and 25 wider at the edges of the pavement, as shown at the left in Fig. 1; and the clamping member for that position may also have its upwardly and downwardly extending flanges 30 48 and 49 longer at the extreme edge of the pavement because the pavement is generally made thicker at its edges.

The flexible expandable members or seals 24 and 26 at the top and bottom of the joint may 35 also be made in sections or lengths corresponding to the shield sections 18, 18a, 18b, etc., as shown in Fig. 1, and this permits accommodation of the length of the joint to the width of the pavement so that there is little possibility 40 of any such error being made in the dimensions of the joint as to cause trouble at the time of installation.

The length of the complete joint may be adjustable, and the gaps 56, 57 may be wider or 45 narrower, without affecting the operation of the joint.

In order to prevent the concrete, when it is poured, from running into the space 58 of the air cushion joint, it is necessary to close the gap 50 at the top and bottom of the joint, which is caused by the absence of the full length of sealing members 24, 26. This may be done by means of blocks of material 59, 60, one located above and the other below the dowel plate 11, at each of 55 the gaps 56 between the lengths of shield and seal.

Blocks 59, 60 may be made of plastic or elastic material, such as tar, asphalt, soft rubber, or sponge rubber, and are initially stiff enough to 60 maintain their shape and to maintain the spacing of the joint during the time the concrete is poured.

These blocks are not, however, stiff enough to resist the expansion of the concrete sections 12 65 and 13, and when the concrete expands the blocks 59 and other blocks in the space 58 become flattened out in the space 58.

Blocks 59 and 60 are of such height that they extend from the dowel plate 11 to the lower 70 flange 29 of the seal 24 or to the upper flange 29 of the seal 26. Thus that aperture into the space is closed, even though there is a gap between the sections of seal.

The blocks 59 and 60 may be substantially as 75

long as the width of the clamps 43, so as to overlap into the shields and seals of the joint.

The joint is also preferably provided with a plurality of other small blocks or strips 61, 62, arranged above and below the dowel plate 11 at regularly spaced points, as shown in Fig. 8, to maintain the spacing of the shield flanges with respect to each other. The clamping members 42 and 43 may then be pushed on the shields 16 and 19 until the shield flanges abut against the blocks 59-62, and the shields are thus held in fixed position.

It should be understood that the width of the space 58 between the shield flanges, that is, the air cushioned space, is such as to permit the expansion desired between the sections of concrete, with enough space left over to provide room for the plastic blocks 59-62 after they have been flattened out.

Should abnormal expansion occur, that is, expansion beyond that expected, during which these asphalt members in the new form of sheets are compressed between the ends of the concrete sections, the asphalt will act as a hydraulic cushion, distributing the force applied between the ends of the concrete sections uniformly over the ends of the sections, so that there is less possibility of damage to the concrete.

It is well known that it is practically impossible to get these concrete section ends or edges absolutely uniform in surface, or to make them plane surfaces parallel to each other. Thus, it is inevitable that the ends of the concrete sections would engage first at some irregularity which would place all of the load on that point, but the presence of the asphalt hydraulic cushion distributes this load over the complete area of the ends of the concrete sections and prevents such damage.

The blocks 59 and 60 are, of course, confined above and below and on all sides, except their ends, and therefore held in place. The blocks 61 and 62 may be secured in place by the use of tie wires or a plastic adhesive composition.

Referring to Figs. 4 and 5, this is a view of an additional improvement or modification in which the gaps at 56, 57 above and below between the seal sections 24, 26, etc., are spanned by short sections of seal, which may be indicated by the numeral 63.

As indicated in Fig. 5, this short section of seal 63 may have its proportions slightly larger so that it is adapted to fit over and overlap the ends of the seal sections 24, 24a, etc. However, as these seals are made of very flexible material, such as copper, even a standard length of the ordinary seal may be forced over the ends of adjacent seal sections and caused to make an approximate fit.

Referring to Figs. 6, 7 and 9, these are views showing the structure of a special clamping member adapted also to secure to the joint the end plate which closes the end of the air cushion space.

This end plate 64 may comprise a sheet metal member of the same height as the air space in the joints and of sufficient width to span this air space and to leave room for attachment of the clamping member 65 and a closure flange 66.

The clamping member is of the same structure as the clamping members 43, 43a, previously described, but may be narrower in width.

The flange 66 comprises a piece of sheet metal, which may be secured to the end plate 64, with a

plurality of spot welds, and which is bent diagonally at 67 until the edge 68 comes into the plane of the outer surface of the end plate 64. This forms a space 69, which is free of concrete, to permit expansion of the concrete toward that edge of the end plate. The sheet metal flange 66 would then be bent backward against the end plate 64 during the expansion of the concrete, having served its function of providing the space 69.

It will thus be observed that I have invented an improved concrete road joint, which may be installed as a unit, but the length of which may readily be varied on the job, so that there is no possibility of trouble due to a few inches variation between the length of the joint supplied and the proper length of the joint. Furthermore, the joints may be provided in sections and assembled on the job and the difficulty of taking the lengths of joints off blueprints and plans and providing the joints with exactly the right length for each position on a widened pavement, at a curved intersection or Y, may be eliminated.

The present joint is adapted to provide both for expansion and contraction, and in the event of abnormal and unexpected expansion the initially plastic asphalt blocks which serve as spacers may act as a hydraulic cushion for preventing damage to the nearest parts of the ends of the pavement sections.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A concrete road joint unit comprising a dowel plate of predetermined length and a pair of shield members carried by said dowel plate, each shield member comprising an upwardly extending flange and a downwardly extending flange, and a pair of horizontal flanges for slidably engaging the dowel plate, and space being provided between said vertical flanges and between the edge of said dowel plate and the junction of said horizontal flanges for initial expansion, and flexible expandable members carried by the upper flanges of said shields and the lower flanges of said shields, said shields being formed in a plurality of sections slidably engaging said dowel plate, and clamping members of sufficient width to span a crack between adjacent sections of shield, said clamping members engaging said horizontal flanges and holding them in tight contact with said dowel plate, said clamping members being provided with downwardly extending legs and laterally projecting feet whereby the joint may be supported stably on the terrain.

2. In a concrete road joint, the combination of a dowel plate extending across the concrete road, with a plurality of shield sections, said shield sections being mounted on one edge of said dowel plate by means of a pair of parallel horizontal flanges slidably engaging said dowel plate, said shields having vertically extending upper and lower flanges substantially spanning the thickness of the concrete roadway, a plurality of clamping members engaging said sections, said clamping members being of sufficient width to span cracks between said sections to assure the

continuity of the shield flange walls in spite of the shortness of the shields relative to the complete length of dowel plate, a plurality of similar sealing sections carried by the opposite edge 5 of said dowel plate and likewise held in position by clamping members, said clamping members being provided with downwardly extending and upwardly extending legs, and said downwardly extending legs having laterally turned feet for 10 stably supporting the concrete road joint.

3. In a concrete road joint, the combination of a dowel plate extending across the concrete road, with a plurality of shield sections, said shield sections being mounted on one edge of said dowel 15 plate by means of a pair of parallel horizontal flanges slidably engaging said dowel plate, said shields having vertically extending upper and lower flanges substantially spanning the thickness of the concrete roadway, a plurality of 20 clamping members engaging said sections, said clamping members being of sufficient width to span cracks between said sections to assure the continuity of the shield flange walls in spite of the shortness of the shields relative to the complete 25 length of dowel plate, a plurality of similar sealing sections carried by the opposite edge of said dowel plate and likewise held in position by clamping members, said clamping members being provided with downwardly extending and 30 upwardly extending legs, said downwardly extending legs having laterally turned feet for stably supporting the concrete road joint, and blocks of relatively stiff plastic material adapted to space the vertical flanges of said shields and 35 provide an air cushion space, said blocks being compressible to provide a hydraulic cushion when concrete expands and compresses the blocks.

4. In a concrete road joint, a load transmission structure adapted to be assembled on the job and 40 made to conform at that time without cutting to varying widths of joints at curves or the like,

comprising a dowel plate adapted to compensate for differences in width of the road at that point, a pair of shield members of flexible sheet metal, each shield member having an upwardly extending flange, a U-shaped fold engaging the 5 dowel plate edge and a downwardly extending flange, said shield members being located on said dowel plate end to end with a predetermined space between the shield members to adjust the combined length thereof to the width of the roadway 10 and a clamping member, said clamping member having a U-shaped fold adapted to bind the flexible U-shaped fold of the shield members in tight sliding engagement with the dowel plate, and said clamping member being of a width 15 adapted to span the crack between the shield members and having upwardly and downwardly extending flanges to effect a closure of all openings between the shield members.

5. In a concrete road joint, the combination of a dowel plate extending across the concrete road, with a plurality of shield sections, said shield sections being mounted on one edge of said dowel plate by means of a pair of parallel horizontal flanges slidably engaging said dowel plate, said shields having vertically extending upper and lower flanges substantially spanning the thickness of the concrete roadway, a plurality of clamping members engaging said sections, said clamping members being of sufficient width to span 20 cracks between said sections to assure the continuity of the shield flange walls in spite of the shortness of the shields relative to the complete 25 length of dowel plate, a plurality of similar sealing sections carried by the opposite edge of said 30 dowel plate and likewise held in position by clamping members, said clamping members being provided with downwardly extending and upwardly 35 extending legs.

CLIFFORD OLDER. 40
